CLAIM

The ornamental design for a scraper to remove food from a plate, as shown and described.

DESCRIPTION

FIG. 1 is a top, right side, front isometric view of scraper to remove food from a plate design;

FIG. 2 is a top plan view thereof;

FIG. 3 is a front elevational view thereof;

FIG. 4 is a side end view;

FIG. 5 is a rear elevational view thereof; and,

FIG. 6 is a bottom plan view thereof.

The broken line showing in FIG. 1 is for illustrative purposes only and forms no part of the claimed design.
